(57) **CLAIM**

I claim the ornamental design for a meter for determining concentration of analytes, as shown and described.

DESCRIPTION

FIG. 1 is a perspective view of the front of a meter for determining concentration of analytes, hereinafter referred to as the meter.

FIG. 2 is a perspective view of the rear of the meter of FIG. 1.

FIG. 3 is a top plan view of the front of the meter of FIG. 1.

FIG. 4 is a view in elevation of the top of the meter of FIG. 1.

FIG. 5 is a view in elevation of the bottom of the meter of FIG. 1.

FIG. 6 is a side view in elevation of the right side of the meter of FIG. 1.

FIG. 7 is a side view in elevation of the left side of the meter of FIG. 1; and,

FIG. 8 is a top plan view of the rear of the meter of FIG. 1.
